UNITED STATES PATENT OFFICE.

JULIUS W. HEGELE, OF DANVILLE, AND HERMAN HEGELE, DECEASED, LATE OF DANVILLE, ILLINOIS, BY LOUISE S. HEGELE, EXECUTRIX, ASSIGNEES TO THE HEGELE ZINC COMPANY, OF DANVILLE, ILLINOIS, A CORPORATION OF ILLINOIS.

ZINC-SMELTING FURNACE.

1,227,050.

Specification of Letters Patent. Patented May 22, 1917.

Application filed November 17, 1913. Serial No. 801,333.

To all whom it may concern:

Be it known that we, JULIUS W. HEGELE, a citizen of the United States, residing at Danville, in the county of Vermilion and 5 State of Illinois, and HERMAN HEGELE, deceased, late a citizen of the United States, residing at said city of Danville, have invented a new and useful Zinc-Smelting Furnace, of which the following is a specification.

10 This invention relates to smelting furnaces and relates particularly to zinc smelting furnaces.

In zinc smelting furnaces of the type to 15 which our invention has particular reference, the retorts are mounted or arranged in rows or series in long combustion chambers, usually built in pairs separated by a permanent center wall of fire clay or similar 20 refractory material, the inner ends of the retorts resting upon and being supported by suitable ledges or brackets formed on said center wall and their outer ends upon bars which extend between and are secured to 25 upright standards or columns usually and preferably made of cast iron, arranged in pairs on opposite sides of the furnace and the upper ends of which are connected by tie rods provided with suitable adjusting 30 nuts, whereby the spaces between the upright standards or columns connected thereto, respectively, may be adjusted.

In use, the lateral sides of the furnace are adapted to be closed by relatively thin temporary walls of fire clay or similar refractory material, which is designed to be broken away and replaced as often as it is desired 35 or necessary to replace said retorts, the upright standards or columns forming a 40 framework to support the top of the furnace, one end of said retorts and the temporary walls.

The top of the furnace is closed by means 45 of a suitable roof made of fire clay or similar refractory material, and usually arched transversely of the furnace, the outer ends of which rest against rigid abutments on the framework formed by the upright standards, and the inner ends of which are connected by skew backs, either formed on, or 50 which rest upon the center wall of the furnace.

It is found in practice that the permanent

center wall of the furnace expands when first heated and then shrinks, such shrinkage causing a lowering of said center wall of from fifteen to twenty inches.

Owing to this shrinkage of the center wall, the roof construction above described is objectionable for the reason that, if the 60 roof is sufficiently strong so that it does not settle with the center wall, a large open space will be formed at the top of the furnace above the retorts through which the heat and products of combustion will pass 65 without coming into contact with the retorts, thus very greatly reducing the efficiency of the furnace or, if the roof is not sufficiently strong to carry its own weight when the support of the center wall is removed by the contraction thereof, said roof 70 will settle with said wall, thereby causing the roof to bulge and crack and may even result in the breaking down of the roof, thus putting the furnace out of business.

The object of the present invention is to overcome the foregoing objectionable features in furnaces of this kind by providing a roof construction which will be free to settle with the center wall of the device 80 without subjecting said roof to any additional strains, and which will operate to maintain a space of uniform and desired size at the top of the furnace above the retorts.

To accomplish this object, a furnace of our invention comprises the various features and details of construction hereinafter described and claimed.

In the accompanying drawing, in which 90 our invention is fully illustrated—

Figure 1 is a transverse, vertical sectional view of a smelting furnace having a roof embodying our invention; and

Fig. 2 is a similar view of a furnace having a roof embodying our invention in modified form.

Referring now to the drawings, A designates the center wall of the furnace, A' the upright standards or columns forming the 100 framework for the side walls of the furnace, a the tie rods which connect the upper ends of said upright standards or columns, A² the temporary side walls of the furnace, and A³ the retorts mounted in said furnace. All 105 of the foregoing parts are old and well

known in the art and will be readily understood by persons familiar with the art without a detailed description thereof. Said parts may be of any desired or approved construction.

As shown in Fig. 1, the roof of the furnace consists of plates or sections 1, preferably made of fire clay or other similar refractory material, the outer ends of which are supported on bars 2 which extend transversely between and are supported by the upright standards or columns A', and the inner ends of which rest on the top of the center wall A, the upper lateral corners of said wall being preferably slightly beveled, as shown at 3, the angle of said bevel being such that, as first installed, the under sides of the plates or sections 1 will lie flat against the same, thus providing a flat bearing for the inner ends of said roof plates. As shown, the supporting bars 2 for said roof plates are made substantially in the form of inverted T-bars, the outer ends of said roof plates resting in the inner angle thereof.

Said roof plates or sections 1 are made of such length that they will extend across the top of the furnace between the bars 2 and the wall A and will overlap said wall a desired distance, and are of such size and shape in cross-section as will impart necessary strength thereto. In practice, we have used roof plates of this character approximately five feet long, twelve inches thick and six inches wide, and have found that they were sufficiently strong.

Said roof plates or sections 1 are also preferably made of such lengths relatively to the width of the furnace that when the furnace is first erected, the inner or adjacent ends of said roof plates will be separated from each other, but will approach each other as they settle, due to the shrinkage of the center wall from the heat, until, at their points of closest approach, they will be separated only by a short distance, thus insuring against disengagement of the outer ends of said roof plates with the bars 2, due to inward endwise movement of said plates or sections.

In said Fig. 1 of the drawings, the position of the parts, as originally erected and before the shrinkage of the center wall by the heat has taken place, is shown in full lines, while the positions thereof after shrinkage of said center wall is shown in dotted lines. It will be noted that, with the roof construction described, a space of substantially uniform size will always be maintained between the upper retorts and the roof, regardless of the shrinkage of the center wall, and also that shrinkage of said center wall will subject said roof plates to no additional stresses or loads, merely imparting a slight sliding movement to said

roof plates or sections relatively to said wall A.

Instead of roof plates formed from a single integral piece of material such as shown in Fig. 1, we contemplate forming said roof plates from a plurality of blocks or tiles made from fire clay or similar refractory material, said blocks being shaped to form a transverse arch and being secured together by means of a suitable clamp.

Referring now particularly to Fig. 2, in which this modification is shown, A⁵ designates the center wall of the furnace, A⁶ the upright standards or columns forming the framework for the outer walls of the furnace, a⁵ the tie rods connecting the upper ends of said standards or columns, A⁷ the temporary side walls of the furnace, and A⁸ the retorts supported within the furnace.

The roof of the furnace consists of a plurality of roof sections A⁹, each consisting of a plurality of blocks 10 secured together to form an arch by means of a suitable clamp, consisting, as shown, of two members 11 and 12 hinged together at 13, the free ends of which are adapted to be drawn together into strong engagement with the outer sides of the end blocks 10 of each roof section A⁹ by means of a tie rod 13, which connect said rods and are provided with adjusting nuts threaded to the ends thereof outside of said clamping members for forcing or drawing them together.

When in position, the inner ends of the roof sections A⁹ rest freely on the center wall A⁵ of the furnace, their outer ends being supported by means of bars 14 secured to and which extend between the upright standards or columns A⁶—said bars being preferably provided on their inner sides with grooves 15 which are engaged by corresponding ribs 16 formed on the outer sides of the outer clamping member 11, thus providing a pivotal support about which said roof sections may turn as the inner ends thereof settle, due to the contraction of the entire wall A⁵ of the furnace.

It will be understood, however, that our invention contemplates the use of any desired or approved form of clamping means.

We claim:

1. A roof for a smelting furnace of the type comprising walls, one having a framework which is practically non-contractible by heat, and the other of which contracts excessively and permanently under heat, said roof comprising sections supported by the framework of said non-contractible wall and by said contractible wall and having tilting engagement with one thereof and sliding engagement with the other, substantially as described.

2. A roof for a smelting furnace of the type comprising walls, one having a framework which is practically non-contractible

- by heat, and the other of which contracts excessively and permanently under heat, said roof comprising sections supported by the framework of said non-contractible wall
5 and by said contractible wall, and having tilting engagement with one said framework and sliding engagement with said contractible wall, substantially as described.
3. A roof for a smelting furnace of the
10 type comprising walls, one having a framework comprising upright metal supports and transverse metal bars supported by and which extend between said supports, and a wall made of fire clay which contracts ex-
15 cessively and permanently under heat, said roof comprising sections supported by trans-

verse members of said framework and by said fire clay wall, and having sliding engagement with said fire clay wall, substantially as described.

20

In testimony whereof we have hereunto set our hands in the presence of two subscribing witnesses, this 10th day of November, A. D. 1913.
